UNITED STATES PATENT OFFICE.

JAMES G. RUSSELL, OF DORCHESTER, MASSACHUSETTS.

FLANGING MACHINE.

Application filed August 14, 1922. Serial No. 581,674.

To all whom it may concern:

Be it known that I, JAMES G. RUSSELL, a citizen of the United States, residing at Dorchester, in the county of Suffolk and 5 State of Massachusetts, have invented certain new and useful Improvements in Flanging Machines, of which the following is a specification.

This invention relates to improvements in flanging machines. More particularly it relates to machines for bending a relatively large and thick plate of metal, such as boiler iron, into cup shape, as for the head of a boiler. By such machines it has been the 10 practice to bend the edge portion of the circular plate, in successive bites or portions, by moving a member about a center located approximately where the bend occurs. This bending member usually has a carrier that 15 moves in the machine on an arc about this center. If a right angled flange is required the bending is done in stages, as for example by successively bending portions around the edge until the part of the plate which is to 20 constitute the flange is inclined at about thirty degrees from the plane of the plate, then repeating the operations around the edge to bend the flange through another 25 30 degrees, and finally by a third trip around the plate bending the metal through another 30 degrees, thus forming a ninety degree 35 flange. The moving member or bender oscillates, one movement accomplishing the bending of a bite, and the next bringing the bender back into initial position, ready to 40 work upon the next portion of the edge when the plate shall have been moved along. Various forms of apparatus have been devised for effecting the oscillating movements 45 of the bender, but all known to me have been of a complicated nature, involving a large cost in make up, and considerable care and attention to keep them in operative condition.

It is among the objects of the present invention to provide a simple but powerful driving mechanism which will force the bender down at proper working speed and then will return it at increased speed to its 50 initial position. Another object is to provide means whereby the degree of movement of the bender can be regulated to any desired amount, with the additional feature of positively and automatically limiting the extreme movement thereof so as to prevent

rupture or damage to the machine in case of carelessness or forgetfulness. A further object of the invention is to provide improved means for holding the material operated upon, to the end that it may be clamped or 60 released, thereby permitting its rapid shifting to new positions, and whereby it may be easily removed without interference by the holding means when the work upon it 65 has been completed.

These objects are attained by providing a segmental rack on a carrier with which a worm gear is always in mesh, so that upon rotation of the worm the carrier is forced to travel in one direction or another. The 70 worm gear is fast on a shaft driven through bevel gears; and arranged loosely on the drive shaft are driving pulleys each of which is adapted to be locked to the shaft by any ordinary or suitable type of clutch 75 controlled by a shifting device which may be operated by hand to engage or release either pulley, although it is a feature of the invention that mechanical means are provided for disengaging the clutch when the 80 desired travel of the bender has been effected. This automatic release is controlled by a system of linkage arranged to function upon the engagement therewith of dogs 85 adjustably mounted on a disk having rotation synchronous with the bender carrier. The dogs can be set so that when the carrier has moved through any desired angle, they will cause the linkage to operate and throw out whichever clutch is at the time engaged, 90 thus stopping the machine. By limiting the amount of adjustment of these dogs so that in their extreme settings they must unfailingly operate to throw out the clutch, overtravel by the carrier is eliminated and the 95 safe operation of the machine is assured. The holding means comprise a clamping block rotatable on a new shaft, which can be moved along its axis toward or away from the material. This shaft is mounted in a head piece which in turn may be rotated on its axis to remove the holding means from the path of the material as it is withdrawn from the machine after being flanged.

One embodiment of the invention is shown in the accompanying drawings, but such disclosure is merely illustrative, and other applications of the principles involved might be made. It is intended that the patent shall 100 105 110

cover, by suitable expression in the appended claims, whatever features of patentable novelty exist in the invention disclosed.

In the drawings:

5 Figure 1 is an elevation of a flanging machine embodying the invention;

Fig. 2 is a similar view in medial section along a portion of the machine;

Fig. 3 is an end view as seen from the left 10 in Fig. 1;

Fig. 4 is a view of the opposite end; and

Fig. 5 is an elevation, partly in section, showing the details of the control mechanism.

15 Referring to the drawings, the material A to be bent or flanged is placed on an anvil or fulcrum block 10, securely mounted between C-shaped side plates 12 of the frame, with its edge under the bender 14 and projecting beyond the anvil a distance equal to 20 the width of the desired flange. The holding block or clamp head 16 is then brought down upon the material by rotation of a screw plunger 18 on which the block is relatively rotatable. The plunger or shaft 18 is threaded in a head piece 20 trunnioned in the side members 12 of the frame thus enabling the clamping plate to be swung up 25 and away from the anvil by a hand lever 22 upon withdrawal of the locating pin 26. This arrangement is desirable in that a screw plunger having a relatively small lead can 30 be employed, whereby the slight movement of the holding block necessary to effect clamping of the work on the anvil and its quick withdrawal to permit shifting of the plate, may be accomplished in less than a revolution of the plunger handle 24 and its complete removal effected by rotation of the 35 head piece. When so removed the pin 26 also serves to hold it out of the way, by engaging in a hole (not shown) in the plunger head piece 20, when the latter has been rotated by the handle 22.

40 With the work securely held on the fulcrum block, as shown in full lines in Fig. 1, the bending operation may be performed by swinging the bender downward about a center, indicated by a dot o, toward the side of 45 the anvil. It has been found advantageous to arrange the fulcrum with respect to this center o, so that when the bender swings about this point, it will in fact slip or wipe over the surface of the plate that is being

50 turned down, in a manner to aid the clamping block in holding the work securely, and to prevent buckling of the material where the bending takes place. The swinging of the bender 14 about the point o is due in 55 fact to a circular movement of its carrier 28 between guides 30 formed one on each side plate 12 of the frame, and constituting, as it were, parallel arcs of circles about an 60 axis passing through the aforementioned center. The perimeter of the carrier is pro-

vided with gear teeth 32 adapted to mesh with a worm fixed on an inclined shaft 36 journaled in suitable bearings 38 supported on a channel plate 40 between the side plates 12. On the upper end of this inclined shaft 70 36 is fixed a bevel 42 which meshes with a similar gear 44 on the end of a horizontal drive shaft 46 suitably mounted on rearward extending frame members 48 and 50. Two driving pulleys 52 and 54 turning 75 loosely upon the drive shaft in opposite directions, one being preferably of greater diameter than the other, are each equipped with a clutch 56 whereby upon shifting the cone 58 along the shaft, either one pulley or the other may be locked to the shaft. The mechanism for shifting the clutch cone is arranged to be operated both by hand and by mechanical means, it being intended that when driving connection is desired the operator will manually move the cone to operate a clutch, and while this connection may be released in a similar manner, it is further provided that the release may be effected mechanically. A groove 60 on the shifter cone is engaged by the yoke end of a rocker arm 62 fixed on a short shaft 64 mounted in the frame members 50, and through one of which it projects to make rigid engagement with the hand lever 65. 85

If the near face of the left hand or large pulley 52 turns toward the base the carrier 28 will move around between its guides in a clockwise direction when this pulley is locked to the shaft 46. Consequently, the bender will swing downward forcing the plate metal toward the side of the anvil. To reverse this direction of travel, the cone clutch is shifted through neutral into engagement with the smaller pulley 54, which, 90 obviously, is arranged to turn in a direction opposite to that of the large pulley. Preferably this smaller pulley rotates at greater speed than the larger pulley 52, so that the return movement of the carrier will be more rapid than its working movement. When a working and a return stroke have been effected the holding block is then released and the plate moved along or around the anvil, 95 depending upon whether a straight or circular flange is being made, to a position where an unbent portion of the plate is in position to be operated upon during the next downward travel of the bender. 100

105 In order to prevent either the operative movement or the return movement of the carrier from going too far, there is control mechanism provided which can be set to disengage either clutch automatically at any predetermined point of travel of the carrier. This mechanism comprises a worm 66 on the end of the drive shaft opposite the bevel gear 44, which worm serves to drive a gear wheel 68 rotatable on a shaft 70, supported upon the horizontal frame members 110 115 120 125 130

48 with its axis at right angles to the axis of the drive shaft. On the front side of this gear wheel, as seen in Figs. 1 and 5, there is provided a circular T-slot 72 within which the heads of T-bolts 74 may be moved nearly around the gear. These bolts are provided with collars 76 which rest on the face of the gear at the sides of the slot opening, and serve both as distance pieces 10 for the thumb nuts 78, so that upon the nuts being tightened the bolt can be clamped in any position around the slot, and as dogs to throw a lever 80 which they encounter as they move with the gear wheel. The lever 15 80 is pivoted loosely on the shaft 70 at one side of the gear wheel and extends downward somewhat below the gear to slotted engagement with one end of a pin 84, the other end of which is similarly connected 20 to a lever 80' on the other side of the gear wheel. This pin 84 is attached at its middle portion to a single lever 86 located between the other two, and rotatable on a shaft 88 journaled in the base members 50. The 25 lever extends upward from the pin to engage one end of a link 90, whose other end is pinned to the rocker arm 62. Upon the hand lever 64 being thrown to move the cone into engagement with a clutch, the 30 rocker arm 62, through link 90, swings the levers 86, 80 and 80' to a position on one side or the other of the vertical according to which clutch is engaged. As heretofore described, upon engagement of either clutch, 35 the drive shaft is rotated, and with it the worm 66 on its end. This immediately causes rotation of the gear wheel, counter-clockwise if the carrier is moving downward and clockwise if the return movement is 40 being effected. In either case it is evident that one of the clamped T-bolts is moving around toward the lever 80. If the bender is operating, the lever 80 will be to the left from the vertical, and the gear wheel will 45 be moving counter clockwise, so that when a T-bolt has moved far enough for its collar to strike the lever, the latter will be pushed back toward the vertical upon continued movement of the gear wheel. This, in turn, 50 acting through the linkage heretofore described, will cause withdrawal of the clutch with consequent stoppage of the drive shaft. The effect is identical when the return movement takes place, and the parts operate 55 reversely.

The worm on the drive shaft and the gear wheel which it rotates are so related to each other and to the inclined worm and segmental gear on the carrier, that when the latter is moved through an arc of approximately ninety degrees, the gear wheel will have rotated through nearly a complete revolution. As shown in Fig. 5 the circular slot does not extend entirely around the face of the gear wheel 68. The purpose of

this is to limit the amount by which the T-bolts 74 can be moved, so that when the bolts are at the extreme ends of the slot, the limit of rotation of the gear is thus fixed, for when either bolt reaches the lever 70 80, it will cause disengagement of whatever clutch has been acting. This total degree of rotation of the gear wheel corresponds to the maximum circular movement of the carrier. As shown in Fig. 1, when the carrier 75 is in one extreme position, the T-bolt is at one end of the slot against the lever with the latter in neutral position. At such time the lever 80 can not be moved to the right, being against the T-bolt and the latter at the end 80 of the slot. Consequently the cone cannot be moved to the right to cause further movement upward of the carrier. With the gear wheel rotated to its other extreme position, that is, when the other T-bolt is against the 85 opposite side of the lever, the cone cannot then be moved to the left to cause further downward travel of the carrier. In this manner, the movement of the carrier is positively limited and the stoppage of travel 90 in either direction is effected automatically by the T-bolts and the linkage operated thereby. If now it is desired to move the carrier only a portion of its possible travel, say to make a bend of thirty degrees, the 95 T-bolt which causes disengagement of the driving pulley is set and clamped at the proper position in the T-slot, shown dotted in Fig. 5, so that it will strike the lever when the carrier has moved its desired distance. By thus merely setting either T-bolt 100 at different locations in the T-slot, any desired limit of travel, in either direction, of the carrier can be obtained. And when so set, the operator need only concern himself with the throwing of the hand lever 62, to start the machine, for the control mechanism will act automatically to stop the carrier 105 when its predetermined limit of movement has been reached.

The simplicity of construction of a machine embodying the features of the present invention makes it relatively inexpensive to build, and the wearing parts are so few in number and can be replaced so readily that the cost of upkeep is correspondingly small. It can be built in any size to accommodate whatever width of flange is desired. The sheet metal and angle iron members provide the requisite strength with the least 110 weight, and this feature, together with the fact that the machine can be driven from any suitable power shaft, enables it to be transportable for both shop and field work. The provision of simple driving means, 115 whereby power is transmitted by mechanical elements without transformation, enables the machine to be operated most efficiently and economically.

I claim as my invention:

1. A flanging machine comprising means for holding material to be flanged, a bender adapted to operate upon material so held, and means for actuating said bender; the 5 said holding means comprising a plunger movable toward and from the material along its own axis, and movable toward and from the material by rotation about an axis at right angles to its own axis, there being 10 means to lock said plunger in different positions around the axis about which it rotates.
2. A flanging machine comprising means for holding material to be flanged, a bender adapted to operate upon material so 15 held, and means for actuating said bender; the said holding means comprising a screw shaft, a clamp head thereon relatively rotatable therewith, and a swivelled member through which said shaft is movable along 20 its own axis and by which it may be swung about an axis at right angles thereto.
3. A flanging machine having means for holding the material to be flanged; a bender adapted to operate upon material so held 25 comprising a segmental gear; means for actuating said bender throughout the whole of its possible travel comprising a worm gear meshing with said segmental gear; and means adapted to release said actuating 30 means short of its maximum travel.
4. A flanging machine having means for holding material to be flanged; a bender adapted to operate upon material so held and having an arcuate gear; and means for 35 actuating said bender comprising a worm meshing with said arcuate gear, a shaft in driving connection with said worm and having a driven pulley loosely mounted thereon, and a clutch for said pulley and shaft, 40 whereby said bender is actuated.
5. A flanging machine having means for holding material to be flanged; a bender adapted to operate upon material so held and having an arcuate gear; means for actuating said bender comprising a worm meshing with said arcuate gear, a shaft in driving connection with said worm and having a driven pulley loosely mounted thereon, a clutch for said pulley and shaft where- 45 by said bender is actuated; and means for automatically disengaging said clutch at a predetermined point of travel of said bender. 50
6. A flanging machine having means for holding material to be flanged; a bender adapted to operate upon material so held 55 and having an arcuate gear; means for actuating said bender comprising a worm meshing with said arcuate gear, a shaft in driving connection with said worm and having a driven pulley loosely mounted thereon, and a clutch adapted to lock either pulley and shaft together, whereby said bender is actuated in opposite directions; and means for automatically disengaging said clutch at a predetermined point of travel of the bender in either direction. 60
7. A flanging machine having means for holding material to be flanged; a bender adapted to operate upon material so held 65 and having a segmental gear; an oblique shaft under the rear of the bender having a worm engaging said segmental gear; a horizontal drive shaft further to the rear in engagement with said oblique shaft; and power connecting and reversing means on said drive shaft. 70
8. A flanging machine having means for holding material to be flanged; a bender adapted to operate upon material so held 75 comprising a segmental gear; an oblique shaft under the rear of the bender having a worm engaging said segmental gear; a horizontal drive shaft further to the rear in engagement with said oblique shaft; power connecting and reversing means on 80 said drive shaft; and a member moving synchronously with the bender and controlling said power connecting and reversing means. 85
9. A flanging machine having a frame of sheet metal and angle iron construction, comprising C-shaped guiding and supporting fins; combined with work holding means arranged between the ends of said fins; a segmental support slidable on said fins, and carrying a bender; angle iron members attached to and extending rearward from said fins; a horizontal drive shaft mounted on said members; and an intermediate shaft supported obliquely between said fins and adapted to transmit power from said drive shaft to said segmental support, whereby said bender moves within the hollow of said fins to operate upon work clamped in the holding means. 90
- Signed at Boston, Massachusetts, this second day of May, 1922.

JAMES G. RUSSELL.
